UNITED STATES PATENT OFFICE.

JOHN THOMAS GORSUCH, OF BALTIMORE, MARYLAND.

CONCRETE SCOW.

1,018,488.

Specification of Letters Patent. Patented Feb. 27, 1912.

Application filed September 6, 1911. Serial No. 647,867.

To all whom it may concern:

Be it known that I, JOHN THOMAS GORSUCH, of Baltimore, State of Maryland, have invented certain new and useful Improvements in Concrete Scows, of which the following is a specification.

My invention relates to that class of scows or the like built of reinforced concrete.

Heretofore many attempts have been made to produce scows of reinforced concrete, but in all such attempts that have come to my attention as the result of careful investigation, I have found to have been a failure, for the reason that the net displacement available is relatively minute for a given size scow, due largely to the fact, that in all types heretofore proposed, heavy concrete walls and bulk heads had to be employed in order to obtain the requisite strength to withstand the stresses and strains met with in practice. I have particularly in mind a scow which is constructed of a concrete hull and deck of the same general design as that disclosed in the drawings of my application, in which the reinforce element consists of L-irons, and as the result, the weight of the finished scow is so great that it displaces so much water as to bring the water line very close to the deck and leave a comparatively small net displacement to take care of the load.

My invention, therefore, primarily has for its object to provide a scow constructed of reinforced concrete in such a manner that the minimum weight may be combined with the maximum strength to obtain a maximum displacement available for the load, and thus for a given size scow increase the cargo carrying capacity thereof over the capacity of those scows constructed along the lines of those heretofore known in the art.

In its general nature the present invention comprises a scow, the hull and deck of which is an integral structure composed of a "form" of open mesh work such for example as is known in the trade as "Clinton wire," which "form" is embedded in concrete; the interior of the hull is divided by a central longitudinal web or bulk head of concrete reinforced by rods so located and designed as to take up the strains and stresses along the bulk head; the interior of the hull on each side of the central longitudinal bulk head being further divided by cross webs to form "open bulk heads" or

walls, which are constructed of concrete embedding truss rods that take up the transverse and longitudinal strains; the interior of the hull is also provided with longitudinal and transverse sills or beams running along the bottom and underside of the deck structure, to which they are integrally formed, these beams or sills being specially reinforced by rods so designed as to take care of the strains and stresses occurring in the sills when the scow is in use, and where the beams or sills cross the lower and upper ones are connected by vertical posts that are also reinforced by rods and from which the longitudinal and transverse bulk head webs radiate.

The invention also resides in the special method of reinforcing the concrete beams, posts and bulk head webs whereby light weight in these parts may be obtained with ample strength to sustain the strains and stresses met with in practice.

The invention furthermore includes those novel details of construction, combination and arrangement of parts, all of which will be first fully described and then be specifically pointed out in the appended claims, and illustrated in the accompanying drawings, in which:

Figure 1 is a top plan view and part horizontal section of the invention. Fig. 2 is an enlarged cross section on the line 2-2 of Fig. 1. Fig. 3 is a horizontal section on the line 3-3 of Fig. 2. Fig. 4 is an enlarged cross section on the line 4-4 of Fig. 1. Fig. 5 is a detail perspective view of a portion of the invention. Fig. 6 is a longitudinal section of one end of the scow. Fig. 7 is a plan view of a portion of the "Clinton mesh" used to make up the form of the scow, that is embedded in the concrete to form the hull and deck walls.

Referring now to the accompanying drawings in which like numerals and letters of reference indicate like parts in all of the figures, 1 designates the hull and 2 the deck, which parts are constructed of concrete 3, embedding a "form" 4 of mesh (Clinton wire or the like, see Fig. 7), the deck being provided with the usual fence 5 constructed of mesh embedded in concrete.

Within the hull, on the bottom thereof, is a set of longitudinal and a set of transverse beams or sills 6, each being formed of concrete, reinforced by straight rods 7 and by "bent" rods 8, the latter extending between

adjacent transverse beams and for a part of their length, lie in the plane containing the rods 7. The rods 8 include inclined portions 9 that terminate in hook-like ends 10, which form "anchors" for the rods. The underside of the deck is also formed with longitudinal and transverse beams or sills 11, of like construction to those 6, on the bottom of the vessel, and they too include a set of straight rods 13 and "bent" rods 14, the rods 13 and 14 being respectively identical with the rods 7 and 8 in their construction.

Where the longitudinal and transverse beams 6 cross one another, and where the 15 longitudinal and transverse beams 11 cross one another, the beams 6 and 11 are united by vertical posts 15 (see Fig. 5), which posts are constructed of concrete and embed four vertical rods 16, whose ends drift into 20 the beams 6 and 11 respectively. Passing through the central portion of the posts 15, and lying in the planes of the beams 6 and 11, are cross rods 17, whose ends 18 project into the beams 6 and 11 respectively and are 25 bent to parallel the same to thereby form anchors. Over the rods 17, and embedding the same, webs of concrete 19 and 20 are formed to radiate from the posts 15, and thereby form "open bulk heads" or partitions, dividing the hull into a plurality of 30 chambers 21, as indicated in Fig. 1 of the drawings. The central bulk head 20 is a continuous unbroken web from bow to stern, while all chambers 21 at a side communicate 35 with one another. It will be seen that the portion of the rods 8 which lies in the plane of the rod 7, is preferably of greater length than the space 22 between the webs 19 at the beams 6 and 11, so as to afford a strong 40 secure bracing for the parts.

Where the webs 19 unit with the side 23 of the hull, a single rod 24 is employed in lieu of the cross rods 17, and the rod 24 is bent into a V-shape, and has its middle portion 25 embedded in the side posts 26, while its "bent" ends 27 are "anchored" in the respective beams 6 and 11.

I have indicated the various reinforcing rods in the drawings as "twisted", but while 50 they have been so indicated, I do not wish to have it understood that I limit myself to the use of twisted rods, as untwisted or straight rods may be employed if desired, or some may be twisted and some untwisted.

55 By making the hull and deck "shell" of a "form" of open mesh, the cross points 28 of which (see Fig. 7) are welded together as in the "Clinton mesh", there will be provided a structure of great strength which 60 will have an inherent tendency to retain its shape so that when it is embedded in the concrete, the resulting structure will be a very firm "shell". By reason of the construction of the "shell", I am enabled to 65 employ light reinforced rods in the beams,

posts and bulk head webs, (a construction that is impossible in other forms of concrete scows now known in the art), and thus render the use of heavy angle irons or L-irons unnecessary. The bow and stern 29 70 of the scow is also reinforced by the diagonal rods 30, whose lower ends are anchored at 31 in the bottom beams 6, and whose upper portions 32 are projected into the ends of the longitudinal beams 11, the portions 32 75 terminating in "bent" over anchor ends 33, as best indicated in Fig. 6 of the drawings.

While the form of the invention illustrated is the preferred one, it is obvious that many changes in the design and proportion 80 of the parts of the scow and the number of chambers, etc., may be made without departing from the spirit of the invention, or the scope of the appended claims.

What I claim is:

1. A boat of the class described, comprising a mesh "hull form" embedded in concrete; a deck over the hull, a set of longitudinal bottom and deck beams, a set of transverse bottom and deck beams, the respective longitudinal and transverse beams crossing one another, vertical posts between the bottom and deck beams at their respective places of crossing, and a solid bulk head of concrete extending from bow to stern in 90 substantially the same direction as the central vertical longitudinal plane of the scow, and cross rods passing centrally through said posts in planes radial thereto and bulk head webs embedding said rods and joining 95 said posts and beams.

2. A boat of the class described, comprising a "hull form" embedded in concrete, a deck over the hull, a set of longitudinal bottom and deck beams, a set of transverse 105 bottom and deck beams, the respective longitudinal and transverse beams crossing one another, vertical posts between the bottom and deck beams at their respective places of crossing, and a solid bulk head of concrete 110 extending from bow to stern and coincident with the central vertical longitudinal plane of the scow, each of said beams and posts having embedded therein a set of straight, reinforcing rods which run parallel to the longitudinal dimension of the respective beam or post and cross rods passing centrally through said posts in planes radial thereto and bulk head webs embedding 115 said rods and joining said posts and beams. 120

3. A boat of the class described, comprising a mesh "hull form" embedded in concrete, a deck over the hull, a set of longitudinal bottom and deck beams, a set of transverse bottom and deck beams, the respective longitudinal and transverse beams crossing one another, vertical posts between the bottom and deck beams at their respective places of crossing, and a continuous 125 bulk head of concrete extending from bow 130

to stern, each of said beams and posts having embedded therein a set of straight reinforcing rods which run parallel to the longitudinal dimension of the respective beam or post, and said beams also including sets of "bent" reinforcing rods, each having a central section running in the horizontal plane of the adjacent straight rods and having other portions "bent" at an angle and terminating in bent over ends to form anchors.

4. A boat of the class described, comprising a mesh "hull form" embedded in concrete, a deck over the hull, a set of longitudinal bottom and deck beams, a set of transverse bottom and deck beams, the respective longitudinal and transverse beams crossing one another, vertical posts between the bottom and deck beams at their respective places of crossing, and a continuous bulk head of concrete extending from bow to stern, each of said beams and posts having embedded therein a set of straight reinforcing rods which run parallel to the longitudinal dimension of the respective beam or post, cross rods passing centrally through said posts in planes radially thereto, and bulk head webs of concrete embedding said cross rods and joining said posts and beams.

5. A boat of the class described, comprising a mesh "hull form" embedded in concrete, a deck over the hull, a set of longitudinal bottom and deck beams, a set of transverse bottom and deck beams, the respective longitudinal and transverse beams crossing one another, vertical posts between the bottom and deck beams at their respective places of crossing, and a continuous bulk head of concrete extending from bow to stern, each of said beams and posts having embedded therein a set of straight reinforcing rods which run parallel to the longitudinal dimension of the respective beam or post, and said beams also including sets of "bent" reinforcing rods, each having a central section running in the horizontal plane of the adjacent straight rods and having other portions "bent" at an angle and terminating in bent over ends to form anchors, cross rods passing centrally through said posts in planes radially thereto, and bulk head webs of concrete embedding said cross rods and joining said posts and beams.

6. In a boat, a hull and deck shell, a set of longitudinal bottom and deck beams, a set of transverse bottom and deck beams, the respective longitudinal and transverse beams crossing one another, vertical posts

between the bottom and deck beams at their respective places of crossing, each of said beams and posts having embedded therein a set of straight reinforcing rods which run parallel to the longitudinal dimension of the respective beam or post, said beams also including sets of "bent" reinforcing rods, each having a central section running in the horizontal plane of the adjacent straight rods and other portions bent at an angle and terminating in anchoring ends.

7. In a boat, a hull shell of reinforced concrete, a deck of reinforced concrete over the hull shell, a set of longitudinal bottom and deck beams, a set of transverse bottom and deck beams, the respective longitudinal and transverse beams crossing one another, vertical posts between the bottom and deck beams at their respective places of crossing, each of said beams and posts having embedded therein a set of straight reinforcing rods which run parallel to the longitudinal dimension of the respective beam or post, cross rods passing centrally through said post in planes radial thereto and bulkhead webs embedding said rods and joining said posts and beams.

8. In a boat, a hull shell of reinforced concrete, a deck of reinforced concrete over the hull shell, a set of longitudinal bottom and deck beams, a set of transverse bottom and deck beams, the respective longitudinal and transverse beams crossing one another, vertical posts between the bottom and deck beams at their respective places of crossing, each of said beams and posts having embedded therein a set of straight reinforcing rods which run parallel to the longitudinal dimension of the respective beam or post, cross rods passing centrally through said post in planes radial thereto and bulkhead webs embedding said rods and joining said posts and beams, said beams also including sets of "bent" reinforcing rods, having a central section running in the horizontal plane of adjacent straight rods and having other portions bent at an angle and terminating in hook-like ends to form anchors, said cross rods anchoring in said beams in the central longitudinal planes of the beams, and said beam rods lying to one side of the central longitudinal plane of the respective beams.
